WAVER

Continuation of application Serial No. 381,575, filed July 27, 1929. This application filed August 13, 1930.
Serial No. 474,993.

This invention relates to an improvement in wavers, and more particularly to a device for producing hair waves, as shown and described in my prior application Serial No. 381,575, filed July 27, 1929, of which this application is a continuation.

Among the principal objects which the invention has in view are: to enable hair to be waved with simultaneously formed parallel crests; to grip the hair at one part and enable a wave to be made by sliding pressure of the operator's finger; to prevent the device from opening when hair is applied therebetween; to readily apply and adjust the device to the hair; to secure simplicity of construction and operation; and to obtain other advantages and results as may be brought out in the following description.

In the drawings:—

Figure 1 is a plan view of my improved hair waving device;

Figure 2 is a similar view, and shows the device applied to a tress of hair;

Figure 3 is a side elevation of the device looking to the left of Figure 1;

Figure 4 is a view looking to the underside of Figure 1;

Figure 5 is a sectional view shown as taken on the line 5—5 of Figure 1;

Figure 6 is a similar view to Figure 5, and shows the device in open position before applying to the hair;

Figure 7 is an end sectional view shown as taken on the line 7—7 of Figure 5;

Figure 8 is a similar view to Figure 7, and shows the retaining member partially open; and

Figure 9 is a similar view to Figures 7 and 8, and shows the retaining member entirely open.

In the specification:

In the specific embodiment of the invention illustrated in the said drawings, the reference numeral 10 indicates my improved device or hair waver in general. Said device is preferably constructed of a plurality of steel wire members bent to give a generally rectangular shape in plan, and arched or bowed in edge view to substantially fit the contour of a person's head which the device

is applied to a tress of hair and a wave in the hair is desired.

The construction of hair waver 10 shown herein may be considered in its general aspect as comprising a pair of members 11, 12, which can be opened with respect to each other for including a tress of hair therebetween. As here illustrated, said members are hinged together at one end, referred to in the following description as the hinged end, and are separable or may be opened at their opposite ends, and thereby having the characteristics of a clamp.

Furthermore, one of the members, which for convenience will be designated as the body member, comprises inner and outer portions 13, 14 respectively, which are fast with respect to each other but longitudinally spaced from each other so as to permit depression of a transverse tress of hair therebetween in a wavy configuration. The major parts of said waver and outer portions are preferably so arranged as to be in a common plane or curved surface, and the outer, or hinged member 12 is arranged to pass through or cross that plane or curved surface of the body portion in closing the hinged member, so that the tress of hair lying across the hinged member will be pushed up between portions of the body portion and assume a wavy configuration, thereby simultaneously forming a pair of parallel crests. Means are provided for retaining the members in this closed position, said retaining means comprising an essential part of the present invention.

As one preferred construction, the body member is bent from a single piece of resilient wire providing substantially parallel side strands 15, 15 with corresponding ends thereof twined inwardly toward each other as at 16. At the opposite ends of the body portion the strands are shown as bent upwardly out of the general plane or surface of the several strands to form half loops 17 by bending the wires inwardly and then back down to the same general plane. These loops determine the distance of passage of the hinged or clamp member past the said general plane or surface in operation, as will

be more fully understood as the description proceeds.

In returning the wire in loops 17, 17, to the said general plane or surface, the same are bent so that the wire in the two loops first approach and then recede from the loop opposite, thereby joining not only upstanding loops but also lateral half loops 18, 18 directed outwardly away from each other.

10 The wire forming the end part of said body portion connects the receding portions of the lateral loops as at 19.

The inner portion of the body portion is likewise preferably bent from a single piece 15 of wire, having major parallel strands 20, 20, not only parallel to each other but also parallel to the side strands of the outer member. Near the hinged end of said member these inner strands 20, 20 diverge as at 21, 21 and 20 provide therebeyond offset parallel parts or hair gripping sections 22, 22 in closer relationship to the outer strands 15, 15 than the major inner strands 20, 20. The ends of the gripping sections 22, 22 bend laterally inward to provide a cross strand or end 23, whereas, at the opposite end of the member the wire integrally connects the inner parallel strands, as at 24.

Contiguous ends of the inner portion and 23 the outer portion of the body portion may be secured permanently together in suitable manner. As here shown, a sheet metal clip 25 is pinched around adjacent connecting cross wires 19 and 24. At the outer end of 23 the member, a more elaborate clip 26 is shown, having opposite ends 27, 27 bent around the outer strands 15, 15 and having longitudinal curled ears 28, 29, one of which, as 28, is pinched around contiguous bent-in ends of both portions of the body portion, and the other of which, as 29, constitutes a hinge socket for the hinge member.

While the hinge or clamp member 12 likewise is preferably of wire with substantially 43 side strands 30, 30, said strands may have a slight convergence toward the releasable end of the member sufficient to obtain certain desired construction and results at opposite ends of the device. At one end of the hinged member the strands bend inward forming hinge pins 31, 31 within said hinge socket 29, whereas at the opposite end of said member the wire forms an integral cross strand 32 between the side strands 30, 30.

53 The parts are preferably so arranged and proportioned that the side strands of the hinged member adjacent the hinged end thereof, substantially bisect the space between the outer strands of the body member and the offset portions of the inner portion of said body members. Furthermore the hinged member is arranged to extend beyond the free end of the body member with its strands thereat spaced at a distance such as 60 to be received by the upstanding loops 17,

17, of the body member, but a less distance apart than the cross wire or end 19 of the body portion. Consequently, to release the engaged ends of the two members, one side strand of the hinged member is first depressed out of the lateral loop 18, as shown in Figures 1 to 8, which acts to draw the other strand into its lateral loop, requiring a torsional distortion of the hinged member in process of release. As soon as the depressed strand passes the protruding shoulder or end of the end strand, continued depression will slide the other side strand out of its lateral loop 17 as shown in full lines in Figure 9 and obtain complete release of that end of the hinged member as shown in dotted lines in the same figure. The tress of hair positioned between the several strands with itself act as a deterrent to either the torsional or lateral movement of the hinged member, and thus obtain a very secure engagement not subject to inadvertent opening in use.

By virtue of the relatively close association of the side strands at the hinged end of the device, a relatively greater grip is obtained upon the tress of hair at that part thereof or end of the wave. This feature is of utmost importance, in that the operator applies a finger pressure to the trees first at the base or hinged end of the device within the space between the inner strands of the body member to pull the hair into a crest, and then by movement of the finger, a longitudinal central crest or wave in the tress between the two parallel crests are mechanically formed simultaneously with each other when the device is closed. The gripping of the tress with this extra force is obtained at the hinged end of the members, thereby utilizing the beneficial leverage provided by the length of the members, and with sufficient ease so as not to be uncomfortable to the person whose hair is being curled. The height of the crest may thus be governed by the amount of hair drawn between the strands at the base end, and since the hair is gripped more securely at that end, more than desired, will not be readily pulled through. With the height of the crest once started, the entire length is then readily obtained with a sliding movement using the parallel strands as a guide.

Claims:

1. A hair waver as characterized comprising a plurality of hair engaging frames disposed in substantially parallel relation for most of their length, the inner sides of said frames being disposed at the hinged end of said waver in closer relation to the outer sides of said frames to form narrow passages therebetween, a looped hair-engaging element being adapted to swing between the inner and outer sides of said frames and through contracted passages formed at the opposite end of said frame, and means lock-

ing the looped element and frame in service position.

2. A hair waver as characterized comprising spaced hair engaging frames, and a looped hair engaging element pivotally supported with respect thereto, said hair engaging frames being substantially parallel for most of their length, the inner frame widening adjacent the end for enabling the operator to insert a finger therein.

3. A hair waver as characterized comprising spaced hair engaging frames, and a looped hair engaging element pivotally supported with respect thereto, said hair engaging frames being substantially parallel most of their length, the inner frame widening adjacent one end enabling the operator to insert a finger therein, said loop widening at its pivoted end to pass between the widened inner frame and the outer frame.

4. A hair waver as characterized comprising a plurality of hair engaging frames hinged at one end, said members adapted to be opened at the opposite end, one of said members having interlocking means at the opening end adapted to be disengaged by a lateral movement of the other said members.

5. A hair waver as characterized comprising a pair of hinged members, said members adapted to be opened at one end, one of said members providing upstanding lateral loops limiting the position of the other member in closed position, and the upstanding lateral loops functioning to retain said other member locked in said upstanding loops.
